DESIGN FOR A COMBINED SHOE SOLE AND HEEL

Henry Clausing, Portsmouth, Ohio, assignor to Vulcan Corporation, Portsmouth, Ohio, a corporation of Ohio

Application June 30, 1942, Serial No. 107,371

Term of patent 7 years

To all whom it may concern:

Be it known that I, Henry Clausing, a citizen of the United States, residing at Portsmouth, in the county of Scioto, State of Ohio, have invented a new, original, and ornamental Design for a Combined Shoe Sole and Heel, of which the following is a specification, reference being had to the accompanying drawing, forming a part thereof.

In the drawing, Fig. 1 is a side perspective view of a combined shoe sole and heel showing my new design.

Fig. 2 is a vertical transverse sectional view of the combined shoe sole and heel taken midway of the length of the heel portion thereof.

The drawing is finished in a manner to indicate contrasting colors or hues of its various parts.

I claim:

The ornamental design for a combined shoe sole and heel, substantially as shown and described.

HENRY CLAUSING.
